UNITED STATES PATENT OFFICE.

JOHN D. RICHARDSON, JR., OF NEWPORT, RHODE ISLAND.

ELECTRIC CALL-BELL.

SPECIFICATION forming part of Letters Patent No. 224,477, dated February 10, 1880.

Application filed December 15, 1879.

To all whom it may concern:

Be it known that I, JOHN D. RICHARDSON, Jr., of Newport, in the county of Newport and State of Rhode Island, have invented a new 5 and useful Improvement in Electric Call-Bells, of which the following is a specification.

My improvements relate to call-bells for telegraph and telephone lines; and the object of the invention is to permit the operation from 10 the central station of any one bell in the circuit, whereby one station may be called without giving an alarm at any of the others.

The invention consists in the use of a second armature with each bell, arranged to require 15 more battery-power for its operation than the armature operating the hammer, and to prevent by its movement the contact of the hammer with the bell, which construction and operation I will more particularly describe with reference 20 to the accompanying drawings, wherein—

Figure 1 is a plan view, and Fig. 2 a vertical section, of my call-bell, and Fig. 3 is a 25 diagram illustrating the arrangement of the circuit.

Similar letters of reference indicate corresponding parts.

A is the magnet, and B the bell, supported upon a standard, a, as shown, in any convenient manner. b is the armature, carrying the 30 hammer c, and fitted with a retractile spring, d, the tension of which is adjustable by a nut, e.

The poles of the magnet A are fitted with extensions f, that project at right angles to 35 ward the bell B; and upon side arms, g, of the standard a is pivoted the second or stop armature h, that is fitted with a retractile spring, i, adjustable by a screw-pin, k. The stop-screw l of the armature h is tapped in the bell-post, 40 and sustains the armature at an angle of about forty-five degrees to the axis of the magnet, and the projecting poles f are formed with a face at about the same angle. From the armature h a bent arm, m, having a forked outer end, 45 extends in the path of the shank of hammer c, and the parts are so adjusted that when the armature h is drawn to the magnet the arm m prevents movement of the armature b and hammer c.

To obtain the desired operation when a number of these bells are placed in one circuit, the retractile spring i of the stop-armature h is to be adjusted so that it will require more battery-power to draw it than is required for armature b, whereby there will be no hinderance to the operation of the bell by a weaker current. The spring of armature b in each instrument will be stronger than the spring of the armature b in the instrument next before it, or nearer to the central station. 50 55 60

The battery at the central station will be arranged in sections with a switch, so that one or more sections can be thrown in circuit. The diagram, Fig. 3, illustrates the arrangement. D is the divided battery. E is a switch, connected to the sections of the battery and fitted with a moving arm, whereby one or more sections can be thrown upon the line; and F are springs to receive a plug for closing the circuit to the distant stations, one of which is 65 70 represented at G.

To call the first station the plug will be inserted in springs F and the arm of switch E turned to connect one section of the battery, giving current sufficient to operate armature 75 b of the instrument of the first station, and the signal may then be given by the key H. The spring of armature h at the first station being strong enough to resist the current, the armature may work and give the call, and there not being battery enough to work the bells at the other stations, they remain silent. If more battery be thrown on the line to call the second station, the armature h of the first station will be moved and prevent the operation of the 80 armature b at the first station, and so on to the last station, where the second armature will not be required. 85 90

Having thus described my invention, I claim as new and desire to secure by Letters Patent—

1. In electric call-bells, a second armature fitted as a stop to arrest the movement of the hammer, combined with a magnet having its poles extended and fitted to attract either or 95 both armatures, all substantially as shown and described.

2. In electric call-bells, the combination, with

magnet A, formed with the extension, poles *f*, of the armature *b*, carrying the bell-hammer, and the armature *h*, fitted with the arm *m*, that arrests the movement of the hammer when both armatures are attracted, substantially as described and shown.

3. In telephone and telegraph lines containing call-bells that require for their operation increase of current proportioned to their distance from the central station, the combination,

with each bell and magnet, of a stop-armature for preventing the call, that is operative only when the current is sufficiently strong to operate the bell at a more distant station, substantially as specified.

JOHN DEAN RICHARDSON, JR.
